UNITED STATES PATENT OFFICE.

LEWIS N. HAINES AND ELMER IRWIN, OF KLAMATH FALLS, OREGON.

PRINT DRIER.

Application filed August 17, 1925. Serial No. 50,760.

To all whom it may concern:

Be it known that we, LEWIS N. HAINES and ELMER IRWIN, citizens of the United States, residing at Klamath Falls, in the 5 county of Klamath, State of Oregon, have invented certain new and useful Improvements in Print Driers; and we do hereby declare the following to be a full, clear, and exact description of the invention, such as 10 will enable others skilled in the art to which it appertains to make and use the same.

This invention relates to new and useful improvements in drying devices, and particularly to devices for drying photographic 15 negatives or prints.

One object of the invention is to provide a device which includes a rotatable element adapted to support a number of photographic negatives or prints, a means for supplying heated air, and novel means for circulating the heated air about the negatives or prints.

Another object is to provide a rotatable element provided with novel means for supporting the negatives or prints in such manner that the negatives or prints form the vanes or blades of the element, and whereby the circulation of heated air is properly and effectively induced to quickly dry the prints.

Other objects and advantages will be apparent from the following description when taken in connection with the accompanying drawings.

In the drawings:

Figure 1 is a side elevation of a drying device made in accordance with the present invention, broken away.

Figure 2 is a front elevation of the device.

Figure 3 is a vertical central sectional 40 view on the line 3—3 of Figure 2.

Figure 4 is a transverse sectional view on the line 4—4 of Figure 1, showing the arrangement of the hot air ducts.

Referring particularly to the accompanying drawings, 10 represents a suitable supporting frame, in which is mounted a drum 11, said drum having approximately one-half of one of its side plates hinged at 12, to the remaining portion, to form the door 13, whereby access is had to the interior of the drum, for a purpose which will be more clearly explained hereinafter. Formed in the lower portion of the curved wall of the drum is a transverse opening 14, and mounted in the frame, and secured to the drum in covering relation to said opening, is a hous-

ing 15, within which are mounted suitable electric heating elements 16. Within the housing 15, and extending in a direction transversely of the drum, is a downwardly curved bottom wall 17. Also mounted in the frame is a motor 18 which drives the transverse shaft 19, by means of the pulley 20 and belt 21. Disposed transversely through the center of the drum 11 is a shaft 22, and fixed on each end portion of the shaft is a spoked wheel 23. Secured to the periphery of each of the wheels 23, and transversely between, are the transversely extending bars 25, in the outer face of each of which is formed a longitudinal channel 26, for the reception of one edge of a negative or print, or a ferrotype plate 27, as shown in the drawings. In the upper periphery of the drum there is formed an opening 28, through which the moisture from the drying prints is adapted to pass, to the atmosphere, a suitable door 29 being arranged for adjustment to regulate the size of the opening. On one end of the shaft 22 is fixed a pulley 30, and engaged around this pulley, and the before-mentioned pulley 20, is a drive belt 31, whereby the motor causes the rotation of the print holder within the drum. The sides of the rotor, within the drum, comprises a pair of circular disks 32, openings 33 being provided for the reception of the wheels 23. Connected to the peripheries of these disks 32, and extending circumferentially of the rotor, is a strip of reticulated material, such as the wire screen 34. Secured to and extending between the disks 32, in parallel relation to the shaft 22, are the connecting bars 24, similar in form to the bars 25, for receiving the outer end edge portions of the prints.

Formed in the opposite side walls of the drum 11 are the hot air ducts 35, which extend from the side portions of the housing 15, to the centers of the side walls of the drum, which are adapted to convey the heated air from the housing into the center of the drum, from whence it passes through the wheels 23, and is thrown outwardly toward the periphery of the rotor, by the prints disposed in the said guides. In the side walls of the rotor are the arcuate and radially extending openings or slots 36, through which the prints or negatives are inserted for engagement with the said guides. In the side walls of the drum, adjacent the centers thereof, are the openings

37, through which the heated air, from the ducts 35, passes into the drum.

The prints, negatives, or ferrotypic plates having been properly slipped into the guides 5 24 and 25, and the door 13 closed, the motor is started and electric current turned on to heat the units 16. The motor rotates the rotor with the result that the prints will 10 drive air through the opening 14, into the housing 15, and into contact with the heating elements 16, from whence the thus heated air will be forced out through the sides of the housing into the ducts 35, and thence into the drum, by means of the central openings 15 37. This heated air passes into contact with the articles to be dried, and is returned to the housing 15 by the action of the prints or negatives, such prints or negatives forming the blades of the fan. Thus the heated 20 air is scooped up by the prints or negatives, as they pass the opening 14, and carried around the interior of the drum, whereby to dry the prints or negatives, such air, together with the moisture evaporated from 25 the wet prints or negatives, passing out through the opening 28.

The prints, negatives, or ferrotypic plates are easily inserted or removed through the slots 36, access to said slots being had by 30 opening the door 13.

What is claimed is:

1. A print drier including a casing, a rotor in the casing, a heating means communicating with the casing, and wet print holding means on the rotor whereby said 35 rotor functions as a fan.

2. A print drier including a casing, a rotor in the casing, a heating means com-

municating with the casing, and means for supporting wet prints on said rotor in position to drive heated air from the heating means into the casing. 40

3. A print drier including a casing, a rotor in the casing, a housing having communication with the casing, heating means in the housing, means for conveying heated air from the housing to the center of the casing, and means on the rotor for supporting wet prints in position to drive heated air from the housing through said ducts as 50 the rotor rotates.

4. A print drier including a casing, a rotor in the casing, a housing connected with and having communication with the casing, heating means in the housing, air ducts on 55 the sides of the casing establishing communication between the casing and the housing, and means on the rotor for holding wet prints in position to act as blades whereby to drive heated air from the housing 60 through said ducts.

5. A print drier including a casing, a rotor in the casing, a housing carried by the casing and having communication with the casing through the periphery thereof, air ducts leading from the housing and entering the centers of the sides of the casing, heating means in the housing, and channeled members on the rotor arranged to support prints in position to drive heated air from the housing through said ducts, and to return such air to the housing. 65

In testimony whereof, we affix our signatures.

LEWIS N. HAINES.
ELMER IRWIN.
